UNITED STATES PATENT OFFICE.

ARTHUR YANCEY, OF NEW ORLEANS, LOUISIANA.

APPARATUS FOR MAKING THE TOP CLOSURES OF ONE-PIECE LINERS FOR CANS OR OTHER RECEPTACLES.

Application filed March 19, 1923. Serial No. 626,112.

In my Patent No. 1,436,748 the one-piece liner and apparatus for making and setting same are fully described.

The present invention has for its object 5 to provide apparatus for folding down over the contents of the receptacle the projecting part, or the division of the liner prearranged for making the top closure.

For the purposes of disclosure and demonstration, I have selected a simple variety 10 of the invention and describe same with the understanding that I am not to be limited to the specific form shown as follows:

Fig. 1 is a view in elevation of a can and liner after the first folding operation has been made.

Fig. 2 is a plan view and section indicated by the dotted line 2—2 Fig. 1.

Fig. 3 is a view in elevation of a can and liner after the second operation of folding 20 has been performed.

Fig. 4 is a plan view and section by the dotted line 4—4 Fig. 3.

Fig. 5 is a view in elevation of a can and liner after the third folding operation has been performed.

Fig. 6 is a plan view and section indicated by the line 6—6 Fig. 5.

Fig. 7 is a view in elevation of a can and liner after the last folding operation has 30 been made with the top closure completed, the liner folded over the contents slightly below the top of the can.

Fig. 8 is a plan view of a can with completed one-piece lining.

Fig. 9 is a view of apparatus in elevation and section indicated by the line 9—9 Fig. 10.

Fig. 10 is a plan view of apparatus and section indicated by the line 10—10 Fig. 9 40 with those parts above the section plane being shown in dotted lines and certain parts below being cut away to show some of the parts in full lines which, obscured from view, otherwise would be shown in dotted lines.

A support or frame may be provided with table 11 with horizontal members 12, 13 and 14, and vertical members 15 and 16.

Sprocket wheels 17 and 18 mounted on 50 the horizontal shaft 19, 20 and 21 mounted on horizontal shaft 22 and wheels 23, 24, 25 and 26 mounted on vertical shafts 27 and 28 are revoluble with corresponding shafts in respective bearings.

For convenient reference the sprocket 55 wheels mounted on horizontal shafts and revolving in vertical planes will be referred to as vertical wheels, and wheels mounted on vertical shafts revolving in horizontal planes will be referred to as horizontal 60 wheels.

Chains 29 connect the vertical sprocket wheels and chains 30 and 31 connect the horizontal sprocket wheels.

All of the wheels are of the same pitch 65 and same number of teeth.

Transmission of power may be applied and governed by the tight and loose pulleys 32 and 33.

Miter gears 34 and 35 provide synchronous 70 motion to the corresponding sprocket wheels and chains.

Corresponding links of the vertical chains are connected by chain bars 36, upon which the folder bars 37 are mounted to slide horizontally. 75

Each of the folder bars aforesaid supports two followers 38 and 39 and a folder 40.

The followers aforesaid are revoluble on their respective pintles 41 and 42 and the 80 folders are mounted to slide vertically on the pins 43.

When the folders are in their positions they rest and slide on the top of the table as shown at 44, and when elevated are held 85 by their weight together with the weight of the followers always in a vertical position as shown at 45.

The lower section of the vertical chains slide in guides 46.

Certain links of one of the horizontal chains are provided with attachments 47 which include each two rounded members 48 and 49.

Certain links of the other horizontal chain 95 are provided with attachments 50 and to these a belt 51 may be fastened.

Supports 52, slidingly held by the frame members 53 and 54, carry the turner bar 55 and the can turners 56.

Springs 57 maintain the turner bar and can turners aforesaid gently pressing toward the center of the machine.

Racks 58, 59 and 60 (shown only in Fig. 9) may be placed in any suitable way to prevent 105 sagging of the chains between the sprockets.

Cams 61 and 62 co-operate with the fol-

lowers aforesaid to slide the folders and supports back and forth across the table as required.

Can rails 63 are provided to support the cans while passing through the machine, and the overflow pan 64 is set to receive surplus liquor which may be forced from the cans during the folding operation and returned to the brine tank, if brine is used.

10 Entrance guards 65, leading from the can line, position the cans to be taken up by the conveyors.

Guard spring 66 may be provided to permit the release of one can and to guide the next following can to the take-up position.

15 Discharge belt pulley (Fig. 10 only) 67 is revolutely mounted to carry the can discharge belt 68 operated by any transmission arrangement to receive the cans from the can rails aforesaid and deliver same at a slightly greater velocity than that of the can conveyors.

20 The one-piece liners made and set in the cans with that part of the liner prearranged for the top closure projecting above the top of the can are shown at 69.

25 The cans are received on the feed apron at 70 and are taken up by the conveyor attachments at 71. A, B, C and D represent the folds or stations at which folds are made.

30 In operation, cans with the one-piece liners 69, Fig. 10, made and set therein as fully described in my Patent 1,436,748 having the divisions extending above the can tops as prearranged for the top closures are received at 70 from the can line (not shown) and are forced by the usual moving belt of the can line to take position in the passage way to be taken up by the conveyor attachments 47 at 71.

35 The conveyor attachment 47, moving in a counter clockwise direction takes up the can at 71, Fig. 10, and forces the same past guard spring 66 which gently acts centrally against the can.

40 As soon as a can is taken up by one of the conveyor attachments 47, another can is forced into position 71 by the line belt (not shown) and thus the can feed operation is 50 constantly repeated.

45 In the drawing the section plane indicated by the line 10—10, Fig. 9, cuts the lower rims of the four vertical sprocket wheels as shown, also one of the folders 40 and also a pair of the followers 38 and 39. To avoid confusion, only that part of the vertical chain below the section plane has been shown.

50 It will be observed that the movement of the cans with that of the feed belt 51, the conveyors 47 and the folders 40 is longitudinally synchronous.

The cans in passing rest upon the rounded points 48 and 49 of the conveyors 47, for

which points rollers may be substituted if desired, and are gently pressed thereupon by action of the springs 57 co-operating with the turner bar 55 and the turner-bar supports 52 slidingly mounted in the frame members 53 and 54.

70 The cans pass from the feed apron (not shown) at 71 to the can rails 63 and are supported thereby during passage of the cans through the machine.

75 When a can and the corresponding folder 40 reach station A, Fig. 10, the follower 38 co-operates with the cam 61 to move the folder bar 37 together with the folder 40 transversely, or across the path of the cans, until the central axis of the folder approximately coincides with the axis of the cans. The bottom of the folder 40 slides over the top of the table 11 and the curved or bevelled bottom of the folder 40 facilitates entrance into the can. The projecting division of the 80 folder is thus bent or folded down as shown in Figs. 1 and 2 the fold having been made in the direction indicated by the arrow A, Figs. 1 and 2.

85 It will be observed that by reason of the 90 vertical movement of the folder 40 on the folder-pin 43 together with the weight of the folder, that the fold of the liner is pressed below the top of the can; also, that the amount of depression can be regulated 95 by the screw and nut on the folder-pin 43.

90 As the can advances longitudinally, the left follower 39 co-operates with the left cam 62, Figs. 9 and 10, to move the folder transversely back upon the table and the 100 curved or bevelled bottom of the folder slides over the flange top of the can and readily rises to the higher level of the table 11. When the return follower 39 has traversed the cam 62, the folder 40 will have 105 returned to its original transverse position.

The can advancing now reaches the first can-turner 56 after station A, Fig. 10.

110 The turner 56 may consist of any suitable material which presents to the moving can a stationary surface and causes the surface of the can to roll thereupon.

115 For example, a No. 1 can is about 8 inches of outer circumference, and therefore when four folds of the liner are to be made, the turners should be 2 inches wide. Thus a No. 1 can would roll 2 inches on the turner surface or turn 90 degrees, as it should turn when four folds are desired. If a greater number of folds are desired, or cans of different diameters used, the turners would be regulated accordingly.

120 At stations B and C, the foregoing operations are repeated.

125 At station D the fourth and last fold is made, after which no turning of the can is required.

After passing station D, the cans with the

top closures completed, the folds having been neatly made preferably about $\frac{1}{8}$ of an inch below the top of the can, may be delivered upon the usual discharge disc, or upon a discharge belt as shown at 68 operating upon pulley 67 which should move at a slightly higher speed than that of the conveyor chain to free the cans from the conveyor attachments. The folders return to the initial position 71 and the synchronous conveyors take up other cans repeating the cycle continuously.

As the diameter of the folder is very nearly the same as the diameter of the receptacle, the folds stay put whether wet or dry. When brine is used, the overflow may be conducted back to the briner by the pan 64. With slight modifications, the machine will operate with square or other shapes of cans or cartons.

Having shown a simple variety of the invention which will suggest many others of the same species, I desire to protect by Letters Patent all combinations which include all of the same or equivalent elements set forth in each of the following combinations claimed:

1. Apparatus for making the top closures of one-piece liners including the combination of a folder operating to traverse the path of cans moving synchronously therewith and to fold down over the contents thereof portions of the liner prearranged to provide the top closure and means for moving the folder and cans as aforesaid.

2. Apparatus for making the top closures of one-piece liners including the combination of means for moving the cans along a determined path, devices moving across the path of the cans at the ends of the latter for folding pre-arranged portions of the liner down over the contents of the can slightly below the top thereof and means for turning the cans to facilitate a plurality of folding operations required to complete the closures.

3. Apparatus for making the top closures of one-piece liners including the combination of a folder operating to traverse the rectilinear path of cans moving synchronously therewith and to fold down over the contents thereof, slightly below the top of said cans, portions of the liner prearranged to provide the top closures, means for moving the folder and cans as aforesaid and means for turning the cans to facilitate a

plurality of folding operations required to complete the closures.

4. An apparatus for closing the ends of one-piece can liners inserted within can bodies, comprising a can conveyer for feeding cans in upright position, a can turning device, and a folding device for progressively folding the end of a one-piece can liner.

5. An apparatus for closing the ends of one-piece can liners, comprising a can conveyer, fixed can-turning devices arranged separately at intervals along said conveyer to be encountered by the cans as they are conveyed, and folding devices for progressively folding an end of a one-piece can liner, all of said mechanisms being actuated in timed relation by a common source of power.

6. An apparatus for closing the ends of one-piece can liners, comprising a can feed, a reciprocal folding device for progressively folding the end of a one-piece can liner arranged within the can, and means for successively presenting an unfolded part of said liner end to said folding device until the entire end has been folded.

7. An apparatus for closing the ends of one-piece can liners arranged within the cans, comprising means for continuously feeding cans past a series of folding stations, a series of folding devices to meet said cans and make a partial fold at each folding station, and means for successively presenting an unfolded part of said liner to said folding devices until the entire end has been closed.

8. An apparatus for closing the ends of one-piece can liners projecting from within the cans, comprising a conveyer for feeding cans in upright position, a can turning device, and a folding device for progressively folding the end of the can liner.

9. The combination of conveying means for moving the cans one after the other along a determined path, means for carrying folder guides along said path in time with said cans, and folders reciprocable along said guides transversely to the cans to repeatedly pass close to the ends of the same, and means for turning the cans repeatedly for a part of a revolution to present variously to said folders a foldable liner extending from within the can to within the sphere of operation of said folders.

ARTHUR YANCEY.
